John I. Ammons
John A. Graumith

BY ATTORNEY

UNITED STATES PATENT OFFICE.

JOHN I. AMMONS, OF CUPERTINO, CALIFORNIA.

POULTRY FOUNTAIN.

Application filed December 27, 1921. Serial No. 525,135.

To all whom it may concern:

Be it known that I, JOHN I. AMMONS, a citizen of the United States, and resident of Cupertino, in the county of Santa Clara and State of California, have invented certain new and useful Improvements in Poultry Fountains, of which the following is a specification.

It is the object of my invention to provide a fountain for poultry wherein the water may be fed out in small quantities proportional to the amount used; in which a large supply of water may be provided in one receptacle; in which the main supply may be kept clean. It is a still further object of my invention to provide a device of the character indicated that may be carried from place to place like a bucket, and that can be easily filled to capacity and easily carried while full.

In the drawings,—

Figure 1 is an end elevation of the device.

Figure 2 is a sectional view on 2—2 of Figure 1.

Referring more particularly to the drawing, I show at 1 a cylindrical sheet metal drum closed at one end as 2 and provided with a handle 3 near its open end 4.

At 5 is shown a strip of sheet metal closing off about one fourth of the front opening 4 and at the lower portion thereof, and thence bent outwardly as at 6 to form a flange, the outer edge of the flange being bent under and backwardly as at 7. The strip 5 is bevelled outwardly at both ends to points beyond the sides of drum 1, whereby to form a substantial support for the device and prevent its tipping when placed in position for use.

A distance back from open end 4 is a partition or curtain 8 dropping down from the upper portion of the drum to a point below the plane of the upper edge of strip 5 as shown at 9.

With the handle located as shown the whole device may be readily held in position under a faucet until it is filled with water. After carrying the device to its destination it may be immediately laid down in a horizontal position as shown in the drawing, whereupon water will flow into compartment 10 and be maintained at a given level as 11 as long as there is a supply of water in the device. 55

This device is simple in construction being made of only five pieces of sheet metal. The drum body 1 is easily formed and end 2 secured thereon. Then it only remains to insert curtain 8 and attach strip 5, and place 60 handle 3 in position.

The placing of curtain 8 is facilitated by first forming a bead 12 in drum 1. The curtain 8 is then slipped into engagement with the bead 12 and soldered in position. 65

It is to be understood, of course, that while I have herein shown and described one particular embodiment of my invention, changes in form and construction may be made within the scope of the appended 70 claim.

I claim:—

A fountain of the character indicated comprising a cylindrical container closed at one end, a sheet metal stop arranged to close off 75 the lower portion of its other end, said stop being extended laterally a distance beyond both sides of said container and having its lower edge turned outwardly a distance and thence inwardly a distance to overlap the 80 bottom of said container, a curtain secured to the upper portion of said container a distance from said stop and curving inwardly therefrom, the highest portion of said curtain extending just below the upper 85 edge of said stop.

JOHN I. AMMONS.
